APPARATUS FOR THE HANDLING OF YARN

Henry Von Kohorn, Scarsdale, N. Y.

Application May 29, 1948, Serial No. 29,963

5 Claims. (Cl. 28—71.5)

1

The present invention relates to an improved apparatus and method for the storing and advancing of yarn or thread and it relates more particularly to an improved continuously advancing thread-storage device and to an improved method of continuously storing and advancing threads or yarns.

In the manufacture of rayon by the viscose process, two systems are now in general use, namely, the package system and the so-called continuous spinning system. In accordance with the package system, viscose is extruded through a multiperforated spinnerette into an acid spin-bath, where the viscose is immediately coagulated to form a multifilament thread which is withdrawn and wound into a package, as up a bobbin, or said thread is wound into a package cake by means of a centrifugal bucket. The package is then removed and placed in a liquid aftertreating machine, where numerous liquids are successively forced under pressure through the package in order to remove all traces of the spinbath and of sulphur, sulphides and other undesirable impurities which are present in the freshly spun rayon thread and to then avify the thread. These liquids generally include hot water, desulphurizing solution, neutralizing solution and solutions of soap or sulphonated oils. The wet after-treated packages of thread are then transferred to a drier, where they are subjected to a closely controlled drying atmosphere. The dried packages are then rewound or may be used in their original form.

The liquid aftertreatment of rayon thread in package form is highly time-consuming and requires numerous manual operations. In contrast to this, the liquid aftertreatment and drying of freshly spun rayon thread by the so-called continuous spinning system consumes only a few minutes and obviates the transferring of packages of thread from the spinning machine to the aftertreating equipment and then to the drying equipment. However, the continuous spinning machines now used or proposed possess numerous disadvantages and very few of these machines have yet been proven to be commercially feasible. One type of continuous spinning machine now in use employs a series of advancing reels for each spinning position, the freshly spun rayon thread being withdrawn from the spin-bath and transported along successively lower advancing reels upon which they are subjected to the desired treating liquids, then dried and then twisted and wound. This type of spinning machine is extremely complex, very costly and

2

difficult to maintain and service. Another type of continuous spinning machine now in use, employs canted cylinders for sorting and advancing the thread. Here again, in order to subject the freshly spun rayon thread to all the aftertreatment processes required for such threads or yarns, several sets of canted cylinders are required, thus entailing the disadvantages already enumerated. It is interesting to note that in the continuous spinning machines above described, a completely independent system for storing and treating such separate thread is required and the threads are treated while traveling in a single layer along predetermined surfaces.

Another type of continuous aftertreating machine includes an endless belt, upon which several threads are individually deposited in accumulated fashion along spaced points. The aftertreating liquids are sprayed upon the threads while they are transported by the belt. This machine also has many drawbacks. The threads are treated in a relaxed condition without controlled tension, thus resulting in a non-uniform product. Further, it is very difficult to subject the belt-carried threads to liquids, and to avoid the thread being washed off the belt or to avoid threads from being floated against each other to produce snarled threads. Where foraminiferous belts are employed, the liquids carry the threads through the belt openings, thereby breaking the individual filaments. Another difficulty is to secure the uniform removal of the thread from the belt.

There have been many other continuous spinning systems proposed, but none of these have as yet sufficiently evidenced their superiority over the package spinning system, to warrant their widespread commercial adoption.

It is, therefore, an object of the present invention to provide an improved apparatus and method for the handling of thread.

Another object of the present invention is to provide an improved apparatus and method for handling a plurality of threads so that they may be continuously advanced in a treatment zone, and while so advanced, exposed to successive treating liquids and dried.

Another object of the present invention is to provide an improved apparatus and method for handling a plurality of threads, whereby the total rate of feed of the thread is relatively large compared to the longitudinal rate of advance of the threads through the selected treating zone.

Another object of the present invention is to provide an improved apparatus for continuously

advancing a plurality of stored threads, said apparatus being simple, reliable, and of low cost.

The above and further objects of the present invention will become apparent from a reading of the following description, together with the accompanying drawings, wherein

Fig. 1 is a side elevation of the improved apparatus;

Fig. 2 is a top plan view thereof;

Fig. 3 is a detailed isometric view of a portion thereof;

Fig. 4 is a detailed fragmentary view showing in detail a modification of the equipment illustrated in Figs. 1 through 3; this modification may be used in the other embodiments;

Fig. 5 is a front elevational view of a second embodiment of the present invention;

Fig. 6 is a top plan view of Fig. 5;

Fig. 7 is a front elevational view of a third embodiment of the present invention;

Fig. 8 is a top plan view of Fig. 7 and;

Fig. 9 is a detailed isometric view of a portion of the apparatus illustrated in Figs. 7 and 8.

The subject invention broadly includes the continuous deposition of yarn upon longitudinally moving and transversely spaced thread-engaging elements; whereby the yarn is longitudinally transported through a zone while supported in said zone in a zig-zag transverse pattern. Preferably, a plurality of threads or yarns are gathered into a planar yarn sheet, and this planar sheet is deposited upon the thread-engaging elements in a transverse zig-zag arrangement, and as such is longitudinally transported through the zone. The yarn, while thus transported in said zig-zag arrangement, may be subjected to successive liquid aftertreating steps and to subsequent drying steps. Thereafter, the yarn can be suitably packed in a finished state.

According to the first and highly preferred embodiment of my invention, I provide two sets or series of thread-supporting or yarn-supporting elements. Each set is connected to a respective endless conveyor. Each conveyor has a longitudinal run, which is designated as a feed run. These feed runs are moved longitudinally from the front inlet or feed-in end of the zone to the outlet or rear end of the zone. These longitudinal runs are designated as the longitudinal feeding paths of said elements. These longitudinal runs are optionally parallel to each other and to the longitudinal direction between said front inlet end and said rear outlet end. These feed runs may be wholly un-parallel to each other, and there may be respective parallel and un-parallel sections. The respective paths of movement of said sets intersect each other at the transverse runs of said endless conveyors, at a front intersection point or line and also at a rear intersection point or line. These intersection points or lines are respectively at the inlet and at the outlet end of said zone. The elements of the respective sets successively cross said intersection lines. This successive crossing is preferably alternate, but the invention is not limited to such alternate crossing.

Between said front intersection line and said longitudinal feed runs, the elements of the respective sets are moved transversely away from each other towards said respective longitudinal feeding paths, in addition to their longitudinal movement towards the outlet end.

Between said longitudinal feed runs and the rear outlet end, the elements of the respective sets are moved transversely towards each other

and away from said longitudinal feeding paths, in addition to their longitudinal movement towards said outlet end.

In the second embodiment of my invention, 5 only one of the conveyors has transverse end-runs, and the other conveyor has lateral end-runs.

In the third embodiment of the invention, the conveyors are located so that the two sets of 10 elements have non-intersecting paths. In this embodiment, the inlet and outlet ends of the zone are defined by respective transverse planes, which are crossed successively by respective elements of different sets, preferably alternately.

15 An inlet thread guide and an outlet thread guide are provided. These thread guides are moved transversely to-and-fro, in order to lay the threads in the respective elements of said two sets in said zig-zag formation at said inlet end and to disengage the threads from said elements at said outlet end. Each said thread-guide is provided with a supplemental thread-guide for maintaining the selected tension in the thread or threads, while they are laid around the 20 elements and disengaged from the elements.

25 In each embodiment, the thread or yarn is preferably supplied continuously at the inlet end and the thread or yarn is preferably removed continuously at the outlet end and the elements 30 are preferably continuously moved in their longitudinal feeding paths.

35 First embodiment, Figs. 1-3, 10 designates the chemical spinning portion of the apparatus, 11 the liquid aftertreating and drying zone, and 12 the winding or coning section.

The chemical spinning section 10 consists of a suitable trough 13 through which is circulated a coagulating bath of any well known type. Immersed in the coagulating bath are a plurality of 40 extrusion devices 14, each of which comprises a suitable spinneret 16, connected by means of a conduit 17 through a filter and metering pump to a source of spinning solution, such as viscose or the like. Associated with each of the extrusion devices 14 is a godet 18 which is mounted on a plate 19, which forms the upper wall of a godet drive housing 20. The godets 18 are connected by means of a suitable shaft to a conventional godet drive mechanism which is positioned in the 45 housing 20. A horizontal, fixed lateral thread guide 21, extending along the length of the trough 13, is positioned above the surface of the coagulating bath and anterior of the godets 18.

The treating zone 11 is provided with identical 55 endless conveyors or belts 22a and 22, which are identical in all respects. These conveyors 22a and 22 may be of any type, such as the roller chain type. Said conveyors 22a and 22 are made of any suitable chemically resistant material.

The longitudinal and horizontal top and bottom runs of conveyors 22a and 22 are parallel to each other. The top return run 23 of belt 22a is located above top feeding run 24 of belt 22. There is equal vertical or transverse spacing between 60 the parallel bottom runs of belts 22a and 22 and their top runs 23 and 24.

Each conveyor 22a and 22 is of trapezoidal shape, with respective transverse end runs 25a and 25. These conveyors may be identical in 65 size and shape.

The conveyors 22a and 22 are spaced laterally from each other, as shown in Figs. 2 and 3. Conveyor 22a has a set or series of lateral yarn-supporting elements 26a which are horizontal and 70 parallel to each other, and which extend lat-

erally towards conveyor 22. Conveyor 22 has a set or series of lateral yarn-supporting elements 26 which are horizontal and parallel to each other, and which extend laterally toward conveyor 22a. These elements 26a and 26 are fixed rigidly to their respective conveyors.

The respective transverse end-runs 25 and 25a are located in respective lateral planes which intersect each other along lateral horizontal lines. For convenience, the transverse end-runs 25 and 25a which are proximate to section 10 are designated as the feed-in or front end-runs and the lateral line of intersection 28 of their respective lateral planes is designated as the front or inlet feed-in intersection point or line. The other transverse end-runs 25 and 25a, which are adjacent section 12, are designated as the rear end-runs, and the point or line of intersection 29 of their respective lateral planes is designated as the rear or outlet intersection line.

The elements 26a are of rod-like shape, and they are identical and equally longitudinally spaced from each other. The elements 26 are identical with elements 26a and of the same equal longitudinal spacing.

As indicated by the arrows in Fig. 1, the respective top runs 23 and 24 are driven in opposed longitudinal directions. Hence the front end-run 25a moves downwardly and to the rear, and the front end-run 25 moves upwardly and to the rear. In this illustration the lateral planes in which each pair of end-runs 25, 25a are located, are perpendicular to each other. Hence the movements of the front end-runs 25a and 25 have equal and opposed vertical or transverse components, and equal longitudinal components in the longitudinal feeding direction. The rear end-runs 25 and 25a have respective movements which have equal and opposed vertical or transverse components and equal longitudinal components in the longitudinal feeding direction. The elements 26a and 26 pass alternately across the front intersection line 28, and also across the rear intersection line 29.

The conveyors 22a and 22 are driven at equal longitudinal speeds.

When an element 26 of one set crosses the front intersection line 28 or the rear intersection line 29, said element 26 is preferably then spaced equally from the proximate elements 26a of the other set. Similarly, when an element 26a crosses either said intersection line 28 or said intersection line 29, said element 26a is preferably then spaced equally from the proximate elements 26.

The conveyors 22 and 22a are provided with respective driven pulleys or sprockets 27 and idler rolls or sprockets. The bottom longitudinal run of conveyor 22a and the top longitudinal run of conveyor 22 are the feed runs.

At the beginning of the operation of the device, all the extruded and coagulated yarns or threads are connected to a respective single element 26 or 26a, which may be located at the front of the front line of intersection 28. Each cylindrical element 26, 26a may be provided with suitable means for maintaining the yarns spaced laterally from each other. For this purpose, and as one example, said elements 26 and 26a may be provided with circumferential grooves or other thread spacing devices. The yarns are fed into zone 11 across a front fixed yarn-guide 37, which has yarn-spacing grooves, for example, which are

longitudinally aligned with the yarn-spacing grooves of elements 26 and 26a.

For convenience, it is assumed that prior to starting the machine, the free ends of all the yarns Y are fixed releasably to a single element 26, which is designated as the holding element, anterior the front line of intersection 28.

The machine is then started so that said holding element 26 crosses line 28, in an upward and rearward movement. As the machine is operated, an element 26a will then cross line 28, in a downward and rearward movement, after said holding element 26 has moved above and rearwardly of line 28. The elements 26 and 26a will thus alternately cross line 28. The yarns Y will thus be transported and held in respective planar sheets, which are in zig-zag formation, between the longitudinal top run 24 of belt 22 and the bottom longitudinal run of belt 22a. These planar yarn sheets will be maintained at fixed angles relative to each other while said planar yarn sheets are transported longitudinally through zone 11.

At the rear end of the zone 11, the holding element 26 will be moved to a position rearwardly of rear intersection line 29. The yarns Y are then detached from said holding elements 26, and said yarns are then led across a fixed guide 38 to the mechanism of zone 12.

The machine can then be operated continuously, while the yarns Y are maintained under suitable selected longitudinal tension rearwardly of line 29, so that the yarns Y are maintained straight and under selected tension in zone 11.

Hence the yarns can be continuously longitudinally transported through zone 11.

When an element 26a is about to cross line 29, the yarns 5 are bent under said elements 26a. Hence as each element 26a crosses line 29, said element 26a releases the yarns Y. Similarly, when an element 26 is about to cross line 29, the yarns Y are bent over said element 26, which releases the yarns as said element 26 moves below line 29.

The front portion of zone or section 11 of the illustrated apparatus is provided with a plurality of liquid spray-devices 30, which are located between the upper run 23 of the belt 22a and the upper run 23 of the other belt 22. The spray-devices 30 extend along the width of the section 11, and they are connected to suitable sources of treating liquids such as liquids for washing, de-acidifying, desulphurizing and avifying the transported yarn. A trough 33 is located between the bottom runs of belts 22 and 22a. This trough 33 is partitioned into sections corresponding to and registering with the respective spray devices 30. Thus the liquids which are sprayed by the devices 30 and which drip from the yarns which are supported by the yarn engaging elements 26 and 26a, fall or drip into the corresponding sections of the trough 33, from which the respective liquids may be removed, replenished and recirculated, or may be dumped.

Following the liquid-treating portion of section 11 of the apparatus, there is provided a dryer housing 34 through which the yarn which is supported by the yarn engaging elements 26 and 26a is transported. A plurality of heating elements, such as steam pipes, 35, are located in the lower part of the housing 34, and a suitable circulating device, not shown, is provided for

suitably circulating the heated air through the housing 34, to more effectively dry the transported yarn.

Following section 11 of the apparatus, there is positioned a winding section 12, which includes a plurality of horizontally spaced bobbin supporting spindles 40 which are supported on brackets 41, each of the spindles 40 being driven by means of a belt 42 which is connected to a rotating drum of any well known type which is encased in the housing 43. Associated with the spindles 40 is a ring spinning traverse mechanism 44 which is vertically reciprocated in a well known manner by a mechanism not shown. A stationary thread guide 46 is disposed above each of the spindles 40. Moreover, another thread guide 48 is associated with each of the thread guides 46 and imparts a substantially right angle turn to the yarn leaving section 11 and directed toward the winding mechanism.

It is noted that, although the longitudinal feeding paths travelled by the yarn engaging elements 26 and 26a while they support the yarn, may be parallel to each other, in the longitudinal runs of the belts 22 and 22a, or these paths may diverge or converge slightly, in order to effect increasing or decreasing tension upon the supported yarn, as desired. For example, the thread-engaging elements 26 and 26a may travel along longitudinal feeding runs converging slightly through the drying housing 34, so that the yarn may be dried while under little tension.

In the event a yarn breaks, either accidentally, or in the regular replacement of the spinnerets 16, or for other reasons, the storage device, which forms part of section 11 may be re-threaded by withdrawing a freshly spun yarn from the corresponding extrusion device 14, leading it over the guide 21, around the corresponding godet 18 and along a respective groove in the guide 37. Thereafter the yarn is tied, or otherwise releasably held in a corresponding yarn-spacing groove of a thread-supporting element 26, which is approaching, but has not reached the front intersection line 28. There may be provided at regular intervals, a thread-supporting element 26, or 26a, which has mounted thereon a suitable device for releasably retaining the yarns, thus facilitating the threading of the storage device.

In Fig. 4 of the drawings, there is illustrated a modification of the apparatus above described, which modification is equally applicable to other embodiments of the invention, which will be hereinafter described. The modification resides specifically in the yarn-supporting elements. More particularly a driven belt 50, corresponding to the belt 22 or 22a in the above described first embodiment, supports a plurality of horizontal rods 51, each of the rods 51 having rotatably and coaxially mounted thereon a tubular yarn-supporting element 52. The base of each of the yarn-supporting elements 52 is provided with a rigidly secured friction wheel 53, which abuts and rides along a track 54 disposed below the belt 50. It is thus apparent that, as the yarn-supporting elements 52 are transported by the belt 50, they are caused to rotate about their respective axes by the track 54 and the wheels 53. It is noted that the track 54 may be disposed either along the upper surfaces or the lower surfaces of the friction wheels 53, thereby to rotate the yarn-supporting elements 52 in clockwise or counter-clockwise direction, as may be desired. Also, the track 54 may be disposed along predetermined portions of the travel of the yarn-sup-

porting elements 52, so that a rotary action can be imparted to them only at desired intervals. Since the yarns which are supported by the rotating elements 52 have their relative positions altered during their travel, the uniformity of treatment is greatly improved. By shaping the surface of track 54 to provide a sinuous contour anterior to and in the drying chamber, a vibrating action is imparted to the sheets of yarns, thereby removing some of the liquid adhering to the yarns and accelerating the drying thereof.

Second embodiments, Figs. 5 and 6.—In this second embodiment, one of the belts is vertical and the other belt is horizontal, instead of using two vertical belts. Hence the vertical belt has transverse end-runs and the horizontal belt has lateral end-runs. As in the first embodiment, the yarn-supporting elements are moved through respective paths which intersect each other at a front or feed-in intersection line, and also at a rear or outlet intersection line. In this embodiment there is provided a trough 60, having circulated therethrough the usual coagulating bath, in which there is immersed a plurality of extrusion devices 61. Associated with each of the extrusion devices 61 is a positively driven godet 63 and a guide member 64.

A thread-storage and transport device is provided in zone or section 65, rearwardly of trough 60. This thread-storage device comprises a belt 65 and a belt 67.

The belt 66 is located in a transverse or vertical plane. It is of trapezoidal shape, with a long longitudinal reverse top run 66a and a short longitudinal bottom feed run 66b. These runs 66a and 66b are located in respective superposed horizontal planes. Thread-supporting rods 68 are fixed rigidly to belt 66 as in the first embodiment subject to the modification of Fig. 4. These rods 68 are optionally lateral and horizontal and equally longitudinally spaced from each other, as in the first embodiment. This belt 66 is mounted on pulleys or rolls which have lateral or horizontal axes, which are perpendicular to the plane of Fig. 5.

The belt 67 is of the ordinary type, which has longitudinal runs of equal length, in the same horizontal plane. This belt 67 is mounted on sprockets or pulleys 67a and 67b which have vertical axes, so that the equal and parallel and longitudinal runs 67r and 67f of belt 67 are located in different vertical planes. The run 67r is the feed run.

Horizontal belt 67 has a set of yarn-supporting and lateral rods 68a, whose inner ends are fixed rigidly to belt 67. Said rods 68a are horizontal and parallel to each other in the parallel longitudinal runs of horizontal belt 67. Said rods 68a diverge from each other at the pulleys or sprockets 67a and 67b.

The rods 68a are always located in the horizontal or lateral plane which is defined by the front intersection line 69 and the rear intersection line 70. The belts 66 and 67 are actuated at equal speeds. The spacing of the inner ends of rods 68a equals the spacing of rods 68. The rods 68 and 68a alternately cross the respective intersection lines 69 and 70, as in the first embodiment. Each rod 68a is given a turning movement immediately before it crosses the respective intersection point 69 or 70. Between the pulleys or sprockets 67a and 67b rods 68a are parallel to rods 68.

The arrows in Figs. 5 and 6 indicate the respective directions of movement of the top run

of belt 66, and the runs 67r and 67f of horizontal belt 67.

Stationary horizontal yarn guides 71 and 72 are provided with a plurality of bores or perforations, corresponding in number to the extrusion devices and godets 61 and 63. These guides 71 and 72 are located adjacent to the intersection lines 68 and 70. A plurality of liquid spray-devices 73 are positioned above the top run of vertical belt 66, and a trough 74 is disposed below the bottom run of belt 66. The trough 74 is partitioned into a plurality of sections corresponding to and registering with the respective liquid spray-devices 73. The belts 66 and 67 extend through a dryer housing 75, which is provided with any suitable heating and air-circulating device, not shown. Following the section 65, there is any well known winding mechanism 76, which may be similar to that illustrated and described in the first embodiment of the present invention.

The operation of the apparatus last described is similar to the first embodiment. The threads or yarns which are extruded by the devices 61, are led over the fixed guide 64, and about positively driven godets 63. Thereafter, said yarns are led through the corresponding bores in the guide 71 toward front intersection line 69, where the yarns are alternately engaged by the yarn-engaging elements 68 and 68a.

As above noted, the rods 68 and 68a preferably alternately cross the front intersection point or line 69. At this intersection point or line 69 the front vertical end-run of vertical belt 63 is moving downwardly and to the rear so that the bottom longitudinal run 66b of vertical belt 66 moves from left to right in the feeding direction. Anterior the intersection point or line 69, the rods 68a are turned in a clockwise direction, as viewed above the horizontal belt 67. This clockwise turning movement of rods 68a is preferably slight or negligible at the intersection point 69, at which the rods 68a have substantially or only a linear longitudinal movement, in which rods 68a are parallel to rods 68.

In order to start the machine of this embodiment, the ends of yarns Y are releasably fixed to a selected holding rod 68 of vertical belt 66, in the front run of belt 66, above and hence in front of the intersection line 69. When the machine is operated, this holding rod 68 initially crosses the line 69, while said holding rod 68 is moving downwardly and rearwardly in the front-run of vertical belt 66.

A rod 68a then crosses line 69, while said crossing rod 68a is parallel or substantially parallel to rods 68. The alternate further crossing of rods 68 and 68a cross line 69 thus stores the yarns in planar sheets in zig-zag formation on the rods 68 which are at the bottom run 66b of vertical belt 66, and on the rods 68a which are in run 67r of horizontal belt 67.

When the holding rod 68 crosses the rear intersection line, the yarns are released from said holding rod 68, and said yarns are connected to the respective devices of section or zone 76.

While so stored and longitudinally transported in zone 65 the yarns are subjected to the liquid after treating by the sprays from devices 73, and the yarns are thereafter dried while passing through the dryer housing 75. In this second embodiment, the yarn-engaging elements may have the feature illustrated in Fig. 4 of the drawing, and suitable tracks may be associated with the yarn-engaging elements, to impart the de-

sired notations thereto. Moreover, the paths travelled by the yarn-engaging elements 68 and 68a while they support the yarns, may converge or diverge in accordance with the tension which it is desired to impart to the yarns during the treatment thereof, in the longitudinal runs of the respective belt.

A third embodiment of the invention is illustrated in Figs. 7 through 9 of the drawings, and differs from the first and second embodiments principally in that the paths travelled by the yarn-engaging elements are laterally spaced and do not intersect each other. Instead, a traversing guide mechanism is provided, which deposits the yarns on and between the sets of yarn-engaging elements in a zig-zag or sinuous pattern, in which fashion the yarns are transported through the respective zone, in the desired liquid after-treating and drying stages.

Third embodiment, Figs. 7-9.—This third embodiment has horizontal and superposed endless belts or conveyors 86 and 86a.

A trough 80, having a coagulating bath circulating therethrough has a plurality of associated extrusion devices 81, thread guide-members 82 and godets 83.

The treating zone 84 has said superposed endless and horizontal belts or conveyors 86 and 86a. Said conveyors 86 and 86a are mounted in rolls or sprockets 85, which rotate about vertical axes.

Belt 86 has rod-like yarn-supporting elements 87, which are turnably connected by hinge-members 88 to belt 86, so that each element 87 can turn only about a horizontal axis relative to belt 86, to a vertical or transverse non-supporting position and to a horizontal or lateral yarn supporting position.

Each hinge-member 88 is provided with conventional spring snap-mechanism. When a yarn-supporting element 87 is turned upwardly from its vertical position, through an angle of slightly more than 45°, said snap-mechanism quickly turns said element 87 to the horizontal yarn-engaging position and releasably maintains said element 87 in said horizontal position. When an element 87 is turned downwardly from its horizontal position, through an angle of slightly more than 45°, said snap-mechanism quickly turns said element 87 to the vertical position, and releasably maintains said element 87 in vertical position. Since this snap-mechanism is conventional, it is not shown.

The belt 86a has corresponding elements and hinge-members, which are respectively designated by the corresponding reference numerals 87a and 88a.

At the front or feed end of the zone 84, respective vertically movable thread-guides 92 and 94 are provided. The inlet guide 92 is located longitudinally rearwardly of guide 94. Each thread-guide 92 and 94 has a series of through-and-through perforations through which respective yarns Y are led. Each perforation has an inlet throat 96.

Guide 92 has a collar 100 at its inner end. A grooved cylindrical cam 98 extends vertically through collar 100. Said cam 98 has a right-hand groove or recess 99 and a left-hand groove or recess 99. These grooves 99 are helical and they intersect each at vertically spaced points. The pitch of each groove 99 varies between the ends of each groove. Cam 98 is rotated continuously in the same direction by a conventional drive 101.

Said cam 98 is provided at its top and bottom with bearings in a fixed housing 97, which has a

11

guide slot for vertically guiding the vertically movable guide 92.

The collar 100 has an internal pin or roll which engages one of the grooves 99 when the guide 92 is moved, vertically downwardly, and said pin or roll engages the other groove 99 when guide 92 is moved vertically upwardly. The shift of said pin or roll from one groove to the other, at the end of the respective vertical movement of guide 92, is well-known.

The guide 94 has a corresponding collar 107, and a corresponding cam 106, which is preferably of less height than cam 98. Cam 106 is rotated by belt and pulley 109. Cam 106 is located turnably in another fixed casing 104, which has a guide slot 103 for guiding the up-and-down movement of anterior guide 94.

In Fig. 9, the right-hand thread 99 downwardly actuates the guide 92, and the left-hand thread 99 upwardly actuates guide 94.

The right-hand thread 99 is of high or coarse pitch at its top portion, so that the initial downward movement of guide 92 from its top portion is rapid. Below this high-pitch top portion, the pitch of right-hand thread 99 decreases towards its bottom end. This decrease is preferably uniform, although the invention is not limited thereto.

The bottom end portion of the left-hand thread 99 is of high or course-pitch and such pitch decreases towards the top end of said left-hand thread preferably uniformly.

Both guides 92 and 94 are simultaneously located in their bottom portions, and also in their top portions.

Said guides 92 and 94 are moved in the same number of strokes per minute between their respective top and bottom portions, but their respective strokes have different periods.

The cam 106 is preferably rotated intermittently, so that intermittent strokes are imparted to anterior guide 94. The cam 98 is rotated continuously at constant speed.

An arm 102 extends from each rod 87 and an arm 102a extends from each rod 102a. These arms 102 and 102a are engaged by corresponding trip mechanisms 88 and 88a so that the rods 87 and 87a are urged from their inactive to their yarn engaging position immediately upon clearing the housing 87. The belts 86 and 86a and the cam 98 are so synchronized that the rods 87 and 87a are swung to their yarn engaging position when the guide 92 is at its upper or lower position respectively.

A similar mechanism is provided at the outlet end for swinging the rods 87 and 87a from their yarn engaging to their inactive positions.

In the respective parallel and longitudinal feed runs of belts 86 and 86a, the yarns pass around and over the upper horizontal rods 87, and around and below the lower horizontal rods 87a. The rods 87 and 87a are staggered in said longitudinal runs.

When this machine is started, the guides 94 and 92 are in their top positions. The yarns Y are led over the fixed guide 82 around the rotatable feed godets 83, the fixed guide 108, and through the perforations of guides 94 and 92. The ends of yarns Y are releasably fixed with suitable lateral spacing, to the horizontally disposed engagement rod 87 which is next adjacent to and located rearwardly of rear guide 92.

The machine is then started. The longitudinal rearward movements of rods 87 and 87a in the

12

longitudinal runs of belts 86 and 86a, are slower than the feed of yarns Y by godets 83.

Hence, when guide 92 is moved down from its top position, the yarns Y would ordinarily be slack in front of the engagement rod 87.

This slack is prevented by the rapid downward movement of anterior guide 94 from its top position. This downward movement of anterior guide 94 is timed so as to keep the yarns taut, under selected tension. When anterior guide 94, which operates as a tension guide, is in its mid-position, the yarns are substantially horizontal between fixed guide 108 and guide 94.

At the end of the downward stroke of the guide 92 rod 87a is swung to a horizontal position and advanced out of the return path of guide 92 and engages the yarns Y. The guide may optionally be held stationary in its bottom position and in its top position, but this is not necessary. At the tops and bottoms of grooves 99, said grooves preferably intersect each other at common points.

In the next upstroke of guide 92 it passes beyond the belt 86 and the following rod 87 is swung into horizontal position and advanced to similarly engage and transport the yarns Y. During said upstroke, the front tension guide 94 is moved upwardly, in timed relation, so as to subject the yarns to selected tension anterior the rear guide 92.

In this embodiment the front intersection line is in the vertical plane in which guide 92 is located. The horizontally disposed rods 87 and 87a alternately cross this front intersection plane, as in the previous embodiments.

Similar vertically reciprocating guides 110 and 111 are provided at the rear or outlet end of the zone. Guide 110 corresponds to guide 92 and guide 111 corresponds to guide 94.

When the engaging rod 87 is next adjacent guide 110, the yarns are disengaged from said engaging rod 87 and led through the bores of guides 110 and 111 to the winding mechanism 117.

The machine is then operated continuously.

When guide 110 is moved to its top position, the next adjacent rod 87 is operated by the trip mechanism 89 which downwardly turns the next adjacent rod 87 to its vertical position.

When guide 110 is moved to its bottom position, the trip mechanism turns the anterior and next adjacent rod 87a to its vertical position. In this embodiment, the rods 87 and 87a alternately cross the rear vertical intersection plane in which guide 110 is vertically reciprocated.

A plurality of suitable spray-devices 112 are positioned above the thread storage and transport zone 84. These devices 112 spray suitable after-treating liquids upon the yarn transported in zone 84. Moreover, disposed below the zone 87 is a trough 113, suitably partitioned to provide a plurality of sections registering with and corresponding to spray devices 112. Following the liquid treating section of the thread storage device 84 is a dryer housing 114, through which the thread is transported, and which is provided with heating elements 115, such as steam pipes or the like, and with any suitable air circulating device.

Following the yarn storage device 84 and the associated liquid spray device 112 and dryer housing 114 is a suitable winding mechanism 117, which may be of the ring spinning type. The winding mechanism 117 includes a plurality of spindles 118, driven by belts 119, which in turn are driven by a drum not shown. A traversing ring guide 120 is associated with each of the spindles 118, and is driven by any well known mechanism,

It should be noted that here again the yarn supporting elements 87 may be rotatably mounted about their longitudinal axes, and suitable tracks provided to cooperate with the rotating yarn engaging elements, to impart any desired rotation thereto. Moreover, the paths travelled by the two sets of yarn engaging elements 87 may be parallel, or may converge or diverge to impart the desired tension to the transported yarns.

In each embodiment, I provide two sets of thread-supporting elements, which are moved longitudinally and continuously through a selected longitudinal path, which has a feed or inlet end, and an outlet end.

At the inlet end, I apply the thread or threads in zig-zag pattern to elements of said two sets, so that the thread or threads are supported on the elements of said two sets, up to said outlet end. At the outlet end, I disengage the thread or threads from said elements.

In the preferred embodiment, as in the second embodiment, the elements of the two sets alternately cross an inlet line at said inlet end, and an outlet line at said outlet end, so that said zig-zag pattern is produced solely by the relative movements of said elements. In such case, the transverse runs of the two transverse conveyors, or the transverse runs of the single transverse conveyor, provide means for applying the yarns in the supporting elements.

In the third embodiment, the elements of the two sets alternately cross a plane at said inlet end and another plane at said outlet end, and I provide additional movable thread-actuating and guiding means to produce said zig-zag pattern.

It is clear that a true method is disclosed herein, which may be practiced by several types of mechanism or by hand.

Preferred embodiments of this invention have been described, but numerous changes and omissions and additions and variations can be made without departing from its scope.

What is claimed is:

1. A thread storage and thread transporting device, said device being adapted and constructed to store the thread in zigzag transverse form and to transport the thread in such form longitudinally from a front inlet of said device to a rear outlet of said device, said device comprising a pair of laterally spaced endless conveyors, each conveyor having a longitudinal feed run and front and rear end runs forming obtuse angles with said feed runs, a set of elongated thread engaging elements supported by each of said conveyors, the respective front and rear end runs of said conveyors confronting and being relatively askew to each other and being laterally spaced a distance greater than the length of said thread engaging elements and the feed runs being laterally and transversely disposed

relative to each other and means for driving said conveyors, whereby said elements are advanced in substantially parallel directions along said feed runs and said thread engaging elements are transported along paths which intersect each other at said inlet and said outlet, diverging from said inlet intersection to said feed runs, transported along said feed runs and then converging toward said outlet intersection, each of said elements being mounted in cantilever fashion on the corresponding conveyor and having its free end extending laterally toward said other conveyor at said points of intersection.

2. A device as claimed in claim 1 wherein said thread engaging elements are supported parallel to each other as they are transported from said inlet intersection to said outlet intersection.

3. A device as claimed in claim 1 wherein the runs of said endless conveyors lie in laterally spaced parallel planes.

4. A device as claimed in claim 1 wherein the runs of said conveyors are substantially trapezoidal in shape.

5. A thread storage and thread transporting device comprising a pair of laterally spaced endless conveyors having trapezoidal runs lying in substantially parallel planes, the bases of said trapezoidal runs being diagonally spaced relative to each other; a plurality of elongated

30 thread engaging elements mounted on each of said conveyors, each of said elements being supported at one end thereof by the corresponding conveyor, and having its other end free and extending in cantilever fashion substantially to said other conveyor, said elements being disposed in staggered relationship on the respective conveyors whereby said elements as they are transported along the diagonal positions of said trapezoidal runs alternately pass between the elements carried by the other conveyor.
